UNITED STATES PATENT OFFICE.

JULIUS J. MELMS AND CHARLES E. WALLACE, OF DETROIT, MICHIGAN; SAID MELMS
ASSIGNOR TO SAID WALLACE.

DESIGN FOR A RING.

Application filed May 5, 1924. Serial No. 9,482. Term of patent 7 years.

To all whom it may concern:

Be it known that we, JULIUS J. MELMS and CHARLES E. WALLACE, citizens of the United States, residing in Detroit, in the county of Wayne and the State of Michigan, have invented a new, original, and ornamental Design for Ring, of which the following is a specification, reference being had to the accompanying drawing, forming a part thereof.

Fig. 1 is a perspective view of a ring showing my design engraved thereon.

Fig. 2 is a cross section taken on the line 2—2 of Fig. 1, showing the contour through

the petals of the flower which approximate the rounded contour of the ring proper.

Fig. 3 is a section on the line 3—3 of Fig. 1, showing the scooped out leaves contrasted with the rounded contour of the remaining portion of the ring.

Fig. 4 is an enlarged elevation of the ring showing the flower portion of the design contrasted with the scooped out leaves.

We claim:

The ornamental design for a ring as shown.

JULIUS J. MELMS.
CHARLES E. WALLACE.
